Primary Examiner — J. Thorn, Sr.(74) Attorney, Agent, or Firm — Leanne Taveggia Farrell; Westman, Champlin & Koehler, P.A.(57) CLAIM

The ornamental design for a garment as shown and described.

DESCRIPTION

FIG. 1 is a perspective of a garment showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The dot-dash-dot broken lines form no part of the claimed design. The dash-dash-dot broken lines represent stitching and form part of the claimed design.

1 Claim, 5 Drawing Sheets(56)
